DESIGN FOR A METAL CORNER LATH

Theodore Russell, Naugatuck, Conn.

Application August 16, 1941, Serial No. 102,896

Term of patent 14 years

To all whom it may concern:

Be it known that I, Theodore Russell, a citizen of the United States, residing in Naugatuck, county of New Haven, and State of Connecticut, have invented a new, original, and ornamental Design for Metal Corner Laths, of which the following is a specification, reference being had to the accompanying drawing, forming part thereof.

Fig. 1 is a perspective view of a metal corner lath, showing my new design.

Fig. 2 is a face view of one side of the same.

Fig. 3 is an end edge view of the same.

I claim:

The ornamental design for a metal corner lath, as shown.

THEODORE RUSSELL.
